UNITED STATES PATENT OFFICE.

ELLIS C. HEALY, OF EAST ORANGE, NEW JERSEY, ASSIGNEE TO NEWMAN CLOCK COMPANY, OF NEW YORK, N. Y., A CORPORATION OF NEW YORK.

ACTUATING MEANS FOR WATCHMEN'S CLOCKS.

1,257,227.

Specification of Letters Patent. Patented Feb. 19, 1918.

Application filed November 20, 1914, Serial No. 873,191. Renewed January 4, 1918. Serial No. 210,376.

To all whom it may concern:

Be it known that I, ELLIS C. HEALY, a citizen of the United States, residing at East Orange, in the county of Essex and State of New Jersey, have invented certain new and useful Improvements in Actuating Means for Watchmen's Clocks, of which the following is a full, clear, and exact description.

This invention, which constitutes the subject matter of this application, relates to a watchman's clock, and more particularly to registers or "detectors" of the portable type. In systems of this character, each station is equipped with a recording key, and the watchman carries the register or clock with him on his rounds. At each station the key belonging thereto is applied to or inserted into the clock and, when properly actuated, makes a record on the record sheet or dial inside the clock; this record visibly indicates the time at which the key was applied.

This invention has for its chief object to provide an improved form of connection between the key proper and the receptacle in which it is normally contained, and particularly in the provision of means to audibly indicate to the watchman when the impression upon the record dial has been completely effected.

Of the various embodiments of which the invention is capable, I have selected for illustration and specific description herein the one which, at the present time, is considered to exhibit the various features of the invention in their most convenient and effective form. This embodiment is illustrated in the accompanying drawings, in which—

Figure 1 is a longitudinal sectional view of my invention with a part of the key broken away to show a portion of its interior construction.

Fig. 2 is a sectional view taken on the line 2—2 of Fig. 1.

Fig. 3 illustrates in perspective the pivotal connection between the key and the containing receptacle.

Fig. 4 illustrates substantially the position of the parts at the moment when the plunger begins to be cammed inwardly to operate the impression producing means contained in the key casing.

Fig. 5 shows a modified form of the means

for effecting an audible indication that the impression means has been actuated.

Referring to the drawings in detail, the character 10 designates a suitable receptacle located at each station to be visited and adapted to contain a key 11, which is pivoted at 12 to said receptacle. The receptacle is provided with a suitable closure 13, hinged or otherwise secured thereto, so as to normally conceal the key from view. In Fig. 1 is illustrated, in dotted lines, a portion of a register or clock 14, provided with a suitable dial 15, upon which the desired impressions are adapted to be made by the key whenever the latter has been inserted into the perforation in the side of the clock. Before describing the details which go to make up the invention, it may be stated that whenever the receptacle 10 is opened the key is manually or automatically turned, upon its hinge 10, to the dotted line position A. It is now in position for the clock or register, carried by the watchman on his rounds, to be applied thereto. As soon as this is done the register is moved to the dotted line position B, but during this movement or part of this movement, the actuating plunger 16, supported in the member 17, will be moved longitudinally with respect to the key, and in doing so will actuate the mechanism, not shown, contained in the key to produce the desired impression upon the record dial. At the moment when the impression has been made (or what amounts to the same thing, when the key has been turned sufficiently far) mechanism is provided which, in conjunction with the plunger, audibly indicates the same. The mechanism for actuating the impression producing means and to audibly indicate the time at which the impression is made I will now proceed to describe.

The plunger supporting member 17 is provided with an extension 18 which is located between the ears 19 projecting from the base support 20. The ears 19 carry the pivot pin 12, which passes through the extension 18, and the key proper, as stated above, is adapted to oscillate about this pivot as a center. The base support 20 is preferably separate from the receptacle and adapted to be secured thereto by any suitable means. The extension 18 is provided with two notches 21 and 22, into which one end

of the spring pressed plunger 23 is adapted to enter. When this plunger 23 is entered into the notch 21 the key is maintained in its normal position in the receptacle. The notch 22, which is capable also of performing the function of holding the key in its outer position, is primarily provided to audibly indicate, by the plunger snapping into it, that the record has been properly impressed upon the paper dial in the clock. To prevent any undue strain being exerted upon the pivotal connection, I provide a chain or other means 24 connected at one end to the receptacle and at the other end to the band 25 which encircles the key casing. While this audible indicating means just described operates admirably, I also illustrate another form of such means which I have chosen to claim specifically herein. This form comprises a member 26 pivoted at 27 to the receptacle whose extreme rearward oscillating movement is limited in this case by its contact with the base 20 and whose outward movement is limited by the projection 32 coming into contact with the bottom of the receptacle. The relation of the parts are preferably such that the plunger 16 will always contact with the face 28 of the member 26 irrespective of the position of the latter. As a result of this construction the member 26 will be in operative position irrespective of the position of the containing receptacle. The member is provided with a shoulder 29, over which the plunger, actuated by the spring 30, is adapted to pass as soon as the impression is made upon the record dial. After passing over the shoulder 29 the end of the plunger strikes against the offset surface 31 of the member 26, thereby audibly indicating that the impression upon the dial has been made.

As illustrated in Fig. 1 the pivoted member 26 is provided with a stop lug 32 which abuts against the back of the key casing and limits the outward swing of the lower end of said member 26, to the end that the face 28 of said member is always in the path of the projecting end of the plunger 26 irrespective of the relative position of the key receptacle 50 with respect to its support.

In Fig. 5 I show a slight modification of the means for effecting the audible indication when the impression producing means has been actuated. In this case the surface 55 against which the plunger 16 strikes after leaving the surface 28 is on the base member 20 and is indicated at 31^a.

It is to be understood that I do not limit myself to the construction shown as many 60 changes may be made in point of detail and other embodiments resorted to without necessarily deviating from the true spirit and scope of my invention.

What I claim is:—

65 1. A receptacle in combination with a key

contained therein and provided with a member through which a pin is adapted to pass to pivot said key to the receptacle, and co-operative means on said key and receptacle for audibly indicating when the key has been oscillated sufficiently about its pivot to effect an operation.

2. A receptacle in combination with a key adapted to contain impression producing means and located in said receptacle, means 7 for pivoting the key to the receptacle so that the key is adapted to oscillate into and out of the same, and means for audibly indicating when the key has been oscillated outwardly sufficiently to actuate the impression 8 producing means comprising a plunger connected to said impression means, and a member provided with a surface for camming the plunger inwardly with respect to said key and provided with an offset against 85 which said plunger is adapted to snap.

3. A receptacle in combination with a key pivotally located in said receptacle and adapted to contain impression producing means therein, a plunger slidable in said key, one 90 end of which is adapted to be operatively connected to said impression producing means and the other end of which projects from the pivotal end of said key, and means secured to said receptacle adapted to cam 95 said plunger inwardly as the key is oscillated outward about its pivot, said means provided with an offset against which said plunger strikes to audibly indicate that the impression producing means has been actuated. 100

4. A receptacle in combination with a key pivotally secured in said receptacle and adapted to contain impression means therein, a plunger slidable in said key, one end 105 of which is adapted to be operatively connected to said impression producing means and the other end of which projects from the pivotal end of said key, and means secured to said receptacle and provided with a surface for camming said plunger inwardly 11 as the key is oscillated outwardly about its pivot, and another surface offset from the first named surface and against which said plunger is adapted to strike for audibly indicating that the impression means has 115 been actuated.

5. A receptacle in combination with a key pivotally secured in said receptacle and adapted to contain impression producing means therein, a plunger slidable in said 12 key, one end of which is adapted to be operatively connected to said impression producing means and the other end of which projects from the pivotal end of said key, and means pivotally secured to said receptacle 125 and provided with a surface for camming said plunger inwardly as the key is oscillated outwardly about its pivot, and another surface offset from the first named surface and against which said plunger is adapted 130

to strike for audibly indicating that the impression means has been actuated, said means containing the first named surface adapted to be oscillated forwardly about its pivot by 5 said plunger to permit the key to return to normal position.

6. A receptacle in combination with a key pivotally secured in said receptacle and adapted to be oscillated about said receptacle to operate the same, said key provided 10

with curved extension in which is contained a notch, and a spring-pressed plunger adapted to engage said notch to hold the key in normal position.

In testimony whereof I affix my signature 15
in the presence of two subscribing witnesses.

ELLIS C. HEALY.
